UNITED STATES PATENT OFFICE.

WILHELM ESPIG, OF BERLIN, GERMANY, ASSIGNOR TO MORITZ HESS, OF SAME PLACE.

BILLIARD-TABLE.

SPECIFICATION forming part of Letters Patent No. 235,419, dated December 14, 1880.

Application filed May 10, 1880. (Model.)

To all whom it may concern:

Be it known that I, WILHELM ESPIG, of the city of Berlin, Kingdom of Prussia, German Empire, have invented a new and useful 5 Improvement in Billiard-Tables, of which the following is a specification.

The object of my invention is to provide a new and useful improvement in billiard-tables, whereby the bed of the billiard-table can be 10 adjusted higher or lower above the floor, and the said table can be extended and provided with a top plate, so as to form a large ordinary table.

The invention consists in a billiard-table 15 provided with sliding extension-frames, which rest in the bed-frame, and can be drawn out and covered with table-boards, so as to form an ordinary table. The bed of this billiard-table is movable, and can be raised by means 20 of a series of bent levers mounted on a shaft at each end of the main supporting-frame of the billiard-table.

In the accompanying drawings, Figure 1 is 25 a partial longitudinal sectional and side elevation of a billiard-table provided with my improvement. Fig. 2 is a view of part of the under side of the billiard-bed and a plan view of a part of the main supporting-frame of the billiard-table. Fig. 3 is a partial side elevation and longitudinal sectional elevation of a 30 billiard-table provided with my improvement, showing one of the extension-frames drawn out and covered with a table-board. Fig. 4 is a partial cross-sectional and end elevation of 35 a billiard-table provided with my improvement, showing the billiard-bed raised. Fig. 5 represents the same, showing the billiard-bed lowered and covered with a table-board.

Similar letters of reference indicate corresponding parts.

The billiard-bed *b* rests on the frame *B*, and is surrounded by the cushion-rail *a* and a frame, *A*. A sliding extension-frame, *H*, consisting of the two sliding bars *i* and the transverse bar *j*, which connects the outer ends of the sliding bars *i*, is fitted at each end of the frame *A* surrounding the bed *b*, the sliding rails *i* passing into recesses in the longitudinal pieces of the bed-frame *A*, and the transverse 45 connecting-bar *j* passing under the projecting 50

top plate or molding *s* of the frame *A*. Blocks *m* are attached to the ends of the transverse connecting-bar *j*, where the same is attached to the sliding bars *i*, which blocks are provided with a threaded or other suitable aperture for receiving a screw or stud on the upper end of a table-leg, *C*, so as to form a support for the outer end of the sliding frame *H* when the same is drawn out. The frame *B* rests upon the main supporting-frame *E*, provided with 55 strong legs *D* in the ordinary manner. One or more pins, *c*, are attached to the under side of the supporting-frame of the bed-plate *b*, and, passing into corresponding sockets or apertures *f* in the base-frame *E*, serve as guides 60 for the upper frame, *B*. A number of arms or levers, *h*, are attached to a shaft, *g*, pivoted in the frame *E*, and one of these arms is provided with a projection, upon which a key, *O*, fits. A shaft, *g*, is arranged at each end of 70 the frame.

The billiard-table can be adjusted as follows: The handle *O* is applied to the projection of the shaft *g*, and the said shaft is rotated in the direction of the arrow *a'*, causing the arms 75 *h h* to rise, which raise the bed *b* high enough to be convenient for the players. The bed *b* now rests on the upper ends of the levers *h*, and is protected against transverse movements by the pins *c c*; but if the billiard-table is to 80 be used as an ordinary table the bed *b* must be lowered, which is accomplished by raising the handle *O*. The frame *E* passes into or behind the frame *B*, as shown in Figs. 3 and 5. The sliding frames *H* are then drawn out, 85 the legs *C* are attached, a large table-board, *r*, is placed upon bed *b*, and corresponding table-boards *r'* are placed upon the sliding frames *H H*.

The bed *b* can be raised by means of screws 90 or other like devices, if desired; and the sliding frames may be left off entirely, or may be replaced by two frames which can be hooked onto the billiard-table, and when detached therefrom may form a complete table by themselves.

I am aware that it is not broadly new to construct a billiard-table so that it may be used for dining and other purposes; but

What I claim as new is—

1. In a billiard-table, the sliding extension-frame H, having rails i, working in recesses of the longitudinal pieces of bed-frame, and a transverse piece, j, working under the projecting molding of bed-frame, in combination with the frames A B E, as and for the purpose described.

2. The vibratory shaft g, having journals in frame E, and arms h O, combined in a bill-

iard-table with a movable bed, b, and pins c, to as and for the purpose specified.

The above specification of my invention signed by me this 9th day of December, 1879.

WILHELM ESPIG.
